CLAIM

The ornamental design for an automatic tapioca balls cooking machine, substantially as shown and described.

DESCRIPTION

FIG. 1 is a top, front, and left side perspective view of the first embodiment of an automatic tapioca balls cooking machine showing the new design;

FIG. 2 is a front view thereof;

FIG. 3 is a left side thereof;

FIG. 4 is a right side view thereof; and,

FIG. 5 is a top view thereof.

Features shown in broken lines in the drawings form no part of the claimed design.

The bottom view and the rear view of the first embodiment of the subject design are omitted since they do not contain ornamental features.

The bottom view and the rear view of the second embodiment of the subject design are omitted since they do not contain ornamental features.
